E. KOLB.
LOCKING DEVICE FOR DOORS.

No. 591,850.

Patented Oct. 19, 1897.

UNITED STATES PATENT OFFICE.

EDWIN KOLB, OF ST. LOUIS, MISSOURI, ASSIGNOR TO THE PAULY JAIL BUILDING AND MANUFACTURING COMPANY, OF SAME PLACE.

LOCKING DEVICE FOR DOORS.

SPECIFICATION forming part of Letters Patent No. 591,850, dated October 19, 1897.

Application filed December 11, 1896. Serial No. 615,348. (No model.)

To all whom it may concern:

Be it known that I, EDWIN KOLB, a citizen of the United States, residing at St. Louis, in the State of Missouri, have invented certain new and useful Improvements in Locking Devices for Jail and Similar Doors, of which the following is a full, clear, and exact description, reference being had to the accompanying drawings, forming a part hereof.

10 My invention has relation to improvements in locking devices for sliding jail-doors; and it consists in the novel arrangement and combination of parts more fully set forth in the specification and pointed out in the claims.

15 In the drawings, Figure 1 is an elevation of a portion of a cell, showing the door closed and my attachment applied thereto. Fig. 2 is a similar view showing the door open and the coöperating parts in position to correspond with the open position of the door. Fig. 3 is a detail section on xx of Fig. 2, and Fig. 4 is a front view of the locking-bar at the point where it coöperates with the locking-lug.

25 The object of my invention is to construct a locking device for sliding jail-doors, wherein a maximum amount of travel can be imparted to the door for a given throw of the operating-lever by which the closing and opening 30 of the door is effected, this desirable result being attained without the necessity of any material reduction in the leverage of the operating-lever, and without the production of any noticeable amount of friction among the 35 several mechanical elements of which the present device is composed.

A further object is to construct a locking device by which several doors can be operated or controlled simultaneously by the same 40 lever.

A further object is to provide means whereby the locking device and the shifting mechanism for the door operate independently of one another.

45 The invention presents advantages apparent from a detailed description thereof, which is as follows:

Referring to the drawings, 1 represents a sliding door carried by rollers 2, adapted to 50 ride on the ledge 3, as is usual in this class of jail-doors. Pivoted to the end of a project-

ing arm 4, carried by the wall of the cell, is a bent lever 5, whose long arm is provided with a laterally-projecting pin 6, adapted to engage suitable notches 7 8, formed along the 55 lower surface of a pivoted latch 9, whereby the lever can be locked in either one of two positions, said lever being adapted to operate the locking device, as will presently appear. The free end of the short arm of the 60 bent lever 5 has pivotally connected thereto the lower end of a link 10, whose upper end is pivotally connected to the free end of one arm of a bell-crank lever 11, carried by the cell-wall, the free end of the opposite arm of 65 said bell-crank being pivotally connected to one end of a second link 12. The opposite end of this link is pivotally secured to the free end of one arm of a second bell-crank lever 13, the free end of whose opposite arm 70 is pivotally secured to the upper end of the locking-bar 14, the latter being provided at one end (lower in this case) as usual with a slit or opening 15, with the wall of one end of which the lug 16, carried by the door, is 75 adapted to engage when the door is closed; thereby preventing the opening of the latter when the locking-bar is in one of its extreme positions. (Lowest position in the present case.) Passing loosely through an opening 80 formed at the upper extremity of the locking-bar is the forward end of a coupling-bar 17, whose opposite or rear end is pivotally secured to the medial or connecting pivot of the toggle-links 18 19, the extremity of one toggle 18 being pivotally connected to the wall or ceiling of the cell, and the extremity of the opposite link 19 being pivotally connected to the jail-door along the upper edge thereof. Carried by the side of the coupling-bar 17 in proximity to the upper end of the locking-bar is 85 a lug or short arm 20 which is adapted, under circumstances to be presently referred to, to engage a corresponding depression 21, formed at the lower edge of a travel-bar 22, thus locking 90 said travel-bar to said coupling-bar. The travel-bar 22 is adapted to slide along suitable rollers 23, carried by brackets 24, secured to the cell-wall.

Fig. 1 shows the door in a closed position 100 and the coupling-bar disengaged from the travel-bar. When the operating-lever 5 is

thrown or swung downwardly (upon its release from the notch 7) and made to engage the notch 8 of the latch 9, as seen in Fig. 2, the several connecting-links and bell-crank 5 levers move in the direction indicated by the arrows in Fig. 1, raising the locking-bar, and causing it to bring the lug 20 of the coupling-bar into engagement with the notch 21 of the travel-bar, and bring the slit 15 opposite the lug 16. The door is now in position to be opened, and this is accomplished by the following mechanism: Pivoted to the projecting arm or bracket 24, carried by the cell-wall, is a door-controlling lever 25, the short arm of which assumes, preferably, the shape of a toothed quadrant or arc 26, the teeth of which mesh with the lower toothed edge of the forward end of the travel-bar. When, therefore, the controlling-lever 25 is tilted or swung 10 in the direction as shown by the arrow in Fig. 1, it will force the travel-bar as indicated, which travel-bar, coupled as it is to the coupling-bar, will carry the latter with it in the same direction; but as the coupling-bar is 15 connected to the pivotal pin of the toggle-links 18 19, it will cause them to first contract to accommodate themselves to the shortest distance from one another of the pivots between which their extreme ends are pivoted, 20 and then upon further movement of the travel-bar, the toggle-links will expand into the position indicated in Fig. 2, carrying the door with them and opening the same to its full extent. To close the door, of course the 25 reverse of these operations takes place, and to lock the door, the operating-lever 5 is restored to its original position into engagement with the notch 7 of the latch 9. It will be seen that with a maximum leverage, and 30 yet with a minimum amount of throw of the short arm of the door-controlling lever 25, a maximum amount of travel is imparted to the door, or series of doors that may be coupled to the travel-bar. This result is due to the 35 toggle connection between the door and the travel-bar.

As seen from the foregoing, the door-controlling lever 25 operates independently of the operating-lever 5 of the locking device, 40 the latter lever serving to couple the door to the travel-bar, which is actuated by the controlling-lever.

It is apparent of course that minor changes might be made in details without departing 45 from the spirit of my invention.

Having described my invention, what I claim is—

1. In a door and locking device therefor, a suitable sliding door, a suitable travel-bar 50 normally disconnected from the door, means for effecting temporary connection between the door and travel-bar, and devices for shifting the travel-bar and door connected thereto, substantially as set forth.
- 65 2. In a door and locking device therefor, a suitable sliding door, a locking-bar for the same, a suitable travel-bar normally discon-

nected from the door, means for effecting temporary connection between the door and travel-bar and simultaneously disengaging 70 the locking-bar from the door, and suitable means for shifting the travel-bar and door connected thereto, substantially as set forth.

3. In a door and locking device therefor, a suitable sliding door, a locking-bar for the 75 same, a suitable travel-bar, means for effecting temporary connection between the door and travel-bar for one position of the locking-bar, and disconnecting the travel-bar for another position of the locking-bar, and suitable 80 means for shifting the travel-bar and door when connected, substantially as set forth.

4. In a door and locking device therefor, a sliding door, a suitable travel-bar, toggle-links between the door and the wall of the cell 85 by which the door is carried, a locking-bar for the door, means for effecting connection between the toggle-links and travel-bar for one position of the locking-bar, and means for shifting the travel-bar and door when connected, substantially as set forth.

5. In a door and locking device therefor, a sliding door, a suitable travel-bar, toggle-links having one extremity connected to the door, and the other to the wall carrying the 95 door, a coupling-bar having one end pivotally connected to the toggle-links, an operating-lever for actuating the opposite end of the coupling-bar and adapted alternately to effect connection between it and the travel-bar and 100 then disconnect the same from said travel-bar, and means for shifting the travel-bar, substantially as set forth.

6. In a door and locking device therefor, a sliding door, a suitable travel-bar, toggle-links having one extremity connected to the door, and the other to the wall on which the 105 door is disposed, a coupling-bar having one end pivotally connected to the toggle-links, a locking-bar for the door, the opposite or free end of the coupling-bar being carried by said locking-bar, an operating-lever for actuating the locking-bar and effecting, for one position of said locking-bar, positive connection between the coupling-bar and travel-bar, 115 and disengaging the said coupling-bar from the travel-bar for another position of the locking-bar, and suitable devices for shifting the travel-bar, substantially as set forth.

7. In a door and locking device therefor, 120 a sliding door, a locking-bar for the same, toggle-links connected respectively with the door and the wall along which the door is disposed, a coupling-bar interposed between the toggle-links and the locking-bar, said coupling-bar being adapted to effect connection between the toggle-links and travel-bar for one position of the locking-bar, and disconnect said parts for another position of the locking-bar, an operating-lever carried by the 125 wall of the cell, and intermediate connecting links and levers between the actuating-lever and the locking-bar for moving the latter for 130 effecting the coupling or uncoupling referred

to between the travel-bar and coupling-bar, substantially as set forth.

8. In a door and locking device therefor, a sliding door, toggle-links connected respectively to the door and to the wall along which the same is mounted, a sliding travel-bar mounted in proximity to the links and door, a locking-bar for the door, a coupling-bar having one end pivoted to the pivotal pin connecting the toggle-links, and the other end passing through a suitable opening formed in the locking-bar, a lug carried by the coupling-bar, and adapted upon the movement of the locking-bar to one of its extreme positions to engage a depression formed in the travel-bar for its reception, suitable means for actuating the locking-bar, a controlling-lever for the travel-bar, and means for retaining the locking-bar in either its locked or unlocked position, the parts operating substantially as and for the purpose set forth.

In testimony whereof I affix my signature in presence of two witnesses.

EDWIN KOLB.
